UNITED STATES PATENT OFFICE.

WILLIAM T. BEATTY, OF FLOSSMOOR, FRANK S. DAVIS, OF HOMewood, AND FRED D. WILSON, OF HARVEY, ILLINOIS; SAID DAVIS AND WILSON ASSIGNEES TO AUSTIN MANUFACTURING COMPANY, OF CHICAGO, ILLINOIS, A CORPORATION OF ILLINOIS.

ROAD-ROLLER MAINTAINER.

Application filed January 2, 1923. Serial No. 610,345.

To all whom it may concern:

Be it known that we, WILLIAM T. BEATTY, FRANK S. DAVIS, and FRED D. WILSON, citizens of the United States, residing, respectively, at Flossmoor, Homewood, and Harvey, in the county of Cook and State of Illinois, have invented a certain new and useful Improvement in Road-Roller Maintainers, of which the following is a specification.

This invention relates to machines used in the upkeep of roads. Its object is to provide a road roller of any number of wheels, more specifically as illustrated a three wheel road roller, with a maintainer, viz.: a combined and alternatively selectable planer or scraper, whereby the machine can plane or scrape and simultaneously roll the surface of a road to be repaired, the roller cooperating with the planer or scraper to provide a tractive control of the blade not heretofore present in such devices.

A further object is to provide a machine which will do this not only without tearing up the road or other worked surface as is usual with conventional tractor devices, but actually combines with the planing or scraping simultaneous rolling which has in prior devices been providable only by a separate operation and by employment of a separate rolling machine. In other words, the generic advantage of the invention lies in the fact that its ground gripping tractor, which propels it and gives the force to its blades, is a roller as well, which while propelling is rolling at the same time—something no other machine has ever done—with the result that while scraping or planing, it is a real roller and always leaves its work packed and rolled into permanent smooth shape, such as can only be done where any other machine is used, no matter how big and powerful, by a separate rolling with a separate roller.

A further object is to provide a positively mounted, though selectively adjustable, pushed blade, thereby securing positive action and control of the blade not heretofore possible.

Stated in concrete form, the reason why the device of this invention hereafter illustrated excels all other devices or tools for maintaining gravel or dirt roads is that, although normally a small one-man machine,

it has the weight of a heavy roller acting as a base or foundation carrying its adjustable blades and it has the power required for the roller, which would not ordinarily be provided for the blades alone, incorporated behind the roller weight to make the blade do the hardest of jobs. Concretely, when using its five foot or minimum length of blade, it can successfully work on about as hard and compact a road as any big powerful grader with a heavy tractor and when the work eases up, the operator can extend its blade to six or seven feet and enlarge its operations. Conversely, if the character of the work changes from easy to hard, the operator simply shortens the operating blade, for if the blade is short enough, the machine can, because of the tractive force of a three or four ton roller incorporated in it be held to almost any job and it has the strength and power to do it.

The invention consists in mechanism capable of attaining the foregoing and other objects; which can be very easily and cheaply made; which is satisfactory in use, and is not readily liable to get out of order. The invention still further consists in many features and details of construction which will be hereafter more fully set forth in the specification and claims.

Referring to the drawings in which like numerals designate the same parts throughout the several views:

Figure 1 is a side elevation of mechanism illustrating this invention in its preferred form.

Figure 2 is a plan view of the device of Figure 1.

Figure 3 is an end view, partially in section, taken on line 3—3 from the left hand end of Figures 1 and 2.

Figure 4 is a side detail view of the mechanism at the extreme left hand end of Figure 1, for adjusting both the angularity and the vertical position of the maintainer blade.

Figure 5 is a plan detail view on the line 5—5 of Figure 4.

Figure 6 is a sectional detail view on the line 6—6 of Figure 1.

Figure 7 is a detail view at or about the line 7—7 of Fig. 2 showing the method of attaching a rod to the engine case.

Figure 8 is a plan view of a modified form of maintainer having adjustable ends.

Figures 9 and 10 are detail views of the hinge for the adjustable blade end and of said blade itself.

The drawings show a conventional form 5 of road roller which is fully described and claimed in an earlier application by W. T. Beatty and Frank S. Davis, Serial Number 606,184, which includes a pair of spaced rear rollers 14, a single front roller 16, a 10 combustion engine case 18, carried by the rollers 14, and attached—through a supplemental frame 20—to the vertical steering post 22 of the yoke 24 which embraces the front roller 16. All the rollers have smooth 15 external circumferences. Roller 16 is as shown in Fig. 2 longer than the distance between rollers 14 and is so placed across the center line of the machine that every part of the road between the extreme outside ends 20 of opposite rollers 14 is effectively acted upon and rolled by one or more of the rollers as the machine passes over a given path whereby this roller, though used to give traction to a scraping blade, also gives a 25 uniform rolling behind the entire width of the minimum length scraping blade (when the extensions 110 are folded back) which is what a separate rolling machine would do if following after any conventional, separate 30 scraping or grading machine, and unless the entire surface behind the blade is uniformly rolled, the result is not commercially considered road rolling at all. In other words, to roll a couple of strips of surface behind 35 the blade as the wheels of a conventional tractor might do if the lugs were taken off, would not accomplish what the machine of this invention does because there would be a gap between the tractor wheels, which in 40 the machine of this invention is rolled by the front roller and the work of these two tractor wheels could not be considered road rolling and would not take the place of road rolling, because road rolling must cover 45 the entire surface and there is no such thing as rolling a road in strips with vacancies in between. The term "road roller" is used in the claims to mean a machine capable of such wide rolling action. The rollers 14 and 50 16 are close enough together longitudinally of the machine and the whole machine is of sufficient weight that sufficient traction exists between the rollers and the ground to insure effective planing or scraping, hereafter described, of the path or road travel, simultaneously with the rolling operation. The rollers 14 and 16 are made of sufficiently 55 large diameter so that real rolling, as distinguished from pushing dirt ahead of them, takes place. The conventional roller referred to also includes a driver's seat or station 26 at the rear of the machine, a hand manipulatable shaft 28, extending from the station to the front of the machine where, 60 through the worm 30 and segment 32, it is

adapted to rock the post 22 and consequently the front roller 16.

In carrying out this invention, a combined scraper-maintainer blade 34 is positioned cross-wise of the central axis of the machine 70 in front of the roller 16 in such manner that this blade can be placed at different angles cross-wise of the axis of the machine, and, consequently, of the road, as shown in full and dotted lines in Figures 2 and 5. It is 75 also so arranged that it can by the use of slots 46 and 50, Fig. 4 be tilted vertically to different angles—this for the purpose of making it adaptable to maintainer or scraper use, as the case may be. 80

In order to insure accurate positive work by the blade, it is mounted for positive pushing by the rolling machine, preferably in front of the machine, thereby keeping the wheel base of the roller relatively short with 85 consequent efficiency of the roller mechanism proper. In the specific embodiment of the mechanism for accomplishing this desired result, the blade proper 34 is more or less permanently attached, by means not entering into this invention, to a parallel carrying frame, specifically an angle bar 36, also extending across the central axis of the machine, and the upper flange of this angle bar is detachably secured by any suitable means, 90 as for instance, bolts 38, to a pair of spaced brackets 40—one located on each side of the roller 16 and in alignment with ground engaging shoes or runners 42 of substantial length, extending toward the rear of the machine well past the roller 16. Each bracket 40 is attached to its adjacent runner 42 by a simple pin 44 and slot 46 connection and a pin 48 and angular slot 50 connection, 95 which in a manner entirely obvious from inspecting Figure 5 permits the angle member 36 and consequently the blade 34 to be adjusted vertically a distance equal to the length of slot 46 and to be adjusted angularly in an arc equal to the upper arm of slot 50, viz: the part above and to the left of bolt 48, Fig. 4. The upper shelf 52 of bracket 40 is cut away in angular lines 54, as clearly shown in Figure 5, so as to permit the maintainer blade 34 to assume the angular dotted line position of Figure 2 with 100 reference to the shoes or runners 42. 110

The blade device 34—36 and the runners 42 form together a U-shape frame and they will be referred to under that designation in some of the claims. The runners constitute a depth gauge for the blade and will be so referred to in some of the claims. 120

This U-shaped frame is attached to the body 18 of the engine by means of two oppositely disposed rods, in the particular case here illustrated, angle irons 56, pivotally supported at the engine body on studs 58 carried by detachable brackets 60 (Fig. 7) 125 attached to certain bolts 62 conventionally, 130

used in the engine construction. The opposite or free swinging ends of these rods 56 are attached to the runners 42 by bolts 64, selectively insertable in holes 66 provided for them along the lengths of the shoes 42, preferably in the forward portions thereof adjacent to the maintainer blade 34. The angular position of the blade 34, shown in dotted lines, Figure 2, is attained by an obvious shifting of a runner 42 from the full line position of Figure 2 and re-bolting it in new position. A maintainer blade 34 of the type described will not operate properly unless the shoes 42, carrying it, are firmly pressed upon the ground and, at the same time, it is necessary that the shoes rock through limited arcs about the bolts 64 in order to allow for obstructions on the surface of the road.

20 The spring mechanism fully shown on Figure 6 is therefore provided for producing these desirable results, the same including a vertically positioned bolt 70 pivotally attached at its lower end 72 to the adjacent runner 42 and reciprocatable through a perforation 74 in the adjacent rod 56, there being provided about the bolt and on opposite sides of the rod 56 compression springs 76 and 78, adjustable as to compression by manipulating the nut 80 of obvious construction. With these devices in position, the shoes 42 are always under proper spring control, regardless of whether the operator is using the mechanism hereafter described to elevate or lower the rods 56.

Whenever the operator changes the angle position of blade 34 by manipulating bolts 64 at an adjacent shoe 42, as heretofore described, it is necessary that the lower end 40 72 of bolt 70 be correspondingly shifted into another one of holes 82 provided for it in the same adjacent shoe 42.

45 Pivottally mounted to each rod 42 at a point 84, somewhere between the spring mechanism 76 and the blade 34, is a vertically extending bar 86 provided with laterally extending lugs 88 through which slides a rod 90 encased in a spring 92, interposed between a lug 94 on said rod and the lower one of said lugs 88.

The upper end of each rod 90 is pivotally connected to a crank arm 96 on a shaft 98, suitably journaled across the front of the frame 20, said shaft carrying a gear segment 55 100 meshing with a worm 102 on a shaft 104 extending back to a point adjacent the operator's seat or station 26 and there provided with suitable mechanism, specifically a hand wheel 106, adapted to be grasped by 60 the operator for the purpose of rotating the shaft 104 to thereby raise or lower, as the case may be, the rods 56 and consequently the U-shaped maintainer frame supported by it.

65 Assuming that the operator manipulates

wheel 106 to force the rods 56 downward, he thereby partly compresses the springs 92 to, under spring control, transmit the desired pressure to the bars 86 and consequently ultimately to the blade 34. The device 70 is preferably so constructed that springs 92 will never be completely compressed, with the result that the blade 34 can, if an obstruction in the road is encountered, spring upward against the action of these springs. 75

Attention is called to the fact that the pivotal points 58 for the rods 56 are so low down on the engine 18 that, assuming the roller is moving to the left, as viewed in Figure 1, an almost direct thrust is exerted on the maintainer blade 34 to push it along the ground. In other words, the rods 56 are so nearly parallel to the ground that practically all of the push of the engine is delivered directly to the blade. 85

Figures 8 and following show an alternative construction in which the maintainer blade is provided at one or both ends with adjustable extension members 110, suitably pivoted as at 112, adapted to be used either in alignment with the blade to thereby increase its working length; or in an alternative position where it is, as shown, swung out of the way of the blade and fastened in such retracted position by any suitable means, as, for instance, the devices 114. Attention is called to the fact that, as clearly shown in the upper half of Figure 8, blade extension member 110 swings back of blade 36 sufficiently far to entirely clear its end, thereby leaving the end of blade 36 free to make a finished, vertical cut in the work being done. 95

100 Either form of maintainer blade, herein referred to, may be provided with an angularly extending plate 116 which makes the maintainer blade more effective.

105 In the operation of the device, an operator sitting on the seat at the rear of the machine manipulates the two hand wheels before him to steer the front wheel of the roller and to raise and lower the maintainer blade. By simultaneously operating the engine control mechanism—not entering into this invention and not shown, to cause the machine as a whole to move, the machine rolls and maintains in a practically continuous operation. 110

115 The rods 56 and the maintainer mechanism controlled by them are maintained in normal position with reference to the central axis of the road roller machine, notwithstanding variations in vertical position as described through the agency of a conventional link or radius rod 120, pivoted to a lug 122 projecting from the engine case and attached to one of the rods 56 at 124. 120

125 If desired, plate 116 may be taken off member 110 and reattached in position 116* when member 110 is swung out of the way as 130

illustrated in Figure 8. In this position, the operator can get his rollers nearer to a curb or the like.

Having thus described our invention, what we claim as new and desire to secure by Letters Patent is:

1. In mechanism of the class described, a road roller carrying an operator's station, a maintainer at an end of the roller, pivoted, vertically, swinging angularly disposed pushing means between the road roller and maintainer and a single means manipulatable by an operator at the station shifting the vertical position of the entire maintainer.
2. In mechanism of the class described, a road roller carrying an operator's station, a maintainer at an end of the roller, angularly disposed pushing means between the road roller and maintainer, means manipulatable by an operator at the station shifting the vertical position of the maintainer, and yielding spring mechanism in the vertical shifting mechanism for the purposes set forth.
3. In mechanism of the class described, in combination, a three wheel road roller, a U-shaped maintainer mechanism, enclosing the front wheel of the roller, pivoted, vertically swinging means by which the roller positively pushes the maintainer, an operator's station on the roller and a single means manipulatable from the operator's station for elevating and depressing the entire maintainer.
4. In mechanism of the class described, in combination, a three wheel road roller, a U-shaped maintainer mechanism enclosing the front wheel of the roller, means pivotally mounted on the roller by which the roller positively pushes the maintainer, an operator's station on the roller and a single means manipulatable from the operator's station for elevating and depressing the entire maintainer.
5. In mechanism of the class described, in combination a three wheel road roller, a U-shaped maintainer mechanism enclosing the front wheel of the roller, inclined push bars approximately horizontal by which the roller positively positions the maintainer, an operator's station on the roller and a single means manipulatable from the operator's station for elevating and depressing the entire maintainer.
6. In mechanism of the class described, in combination, a three wheel road roller, a U-shaped maintainer mechanism enclosing the front wheel of the roller and resting on the ground, means pivotally attached to the side arms of the U-shaped maintainer mechanism connecting it with points on the road roller intermediate of its ends, an operator's station on the roller, and means manipulatable from the operator's station, engaging the supporting means for the maintainer mechanism for elevating and depressing the maintainer.
7. In mechanism of the class described, in combination, a three wheel road roller, a U-shaped maintainer mechanism enclosing the front wheel of the roller and resting on the ground, means pivotally attached to the side arms of the U-shaped maintainer mechanism connecting it with points on the road roller intermediate of its ends, an operator's station on the roller, means manipulatable from the operator's station, engaging the supporting means for the maintainer mechanism for elevating and depressing the maintainer, and yielding mechanism in the elevating and depressing mechanism for the purposes set forth.
8. In mechanism of the class described, in combination a three wheel road roller, a U-shaped maintainer mechanism, enclosing the front wheel of the roller and resting on the ground, means pivotally attached to the maintainer mechanism, connecting it with points on the road roller intermediate of its ends, an operator's station on the roller, and means manipulatable from the operator's station engaging the supporting means for the maintainer mechanism for elevating and depressing the maintainer.
9. In mechanism of the class described, in combination a three wheel road roller, a U-shaped maintainer mechanism enclosing the front wheel of the roller and resting on the ground, means pivotally attached to the maintainer mechanism connecting it with points on the road roller intermediate of its ends, an operator's station on the roller, means manipulatable from the operator's station, engaging the supporting means for the maintainer mechanism for elevating and depressing the maintainer, and yielding mechanism in the elevating and depressing mechanism, for the purposes set forth.
10. In mechanism of the class described, in combination, a three wheel road roller, a U-shaped maintainer mechanism enclosing the front wheel of the roller and resting on the ground, means pressing the maintainer mechanism toward the ground at four separated points, connecting it with points on the road roller intermediate of its ends, an operator's station on the roller and means manipulatable from the operator's station engaging the connecting means for the maintainer mechanism for elevating and depressing the maintainer.
11. In mechanism of the class described, in combination, a three wheel road roller, a U-shaped maintainer mechanism enclosing the front wheel of the roller and resting on the ground, means pressing the maintainer mechanism toward the ground at four separated points, connecting it with points on the road roller intermediate of its ends, an operator's station on the roller, means ma-

- 5 nippulatable from the operator's station engaging the connecting means for the maintainer mechanism for elevating and depressing the maintainer, and yielding mechanism in the elevating and depressing mechanism, for the purposes set forth.
- 10 12. In mechanism of the class described, a three wheel road roller, two wheels at one end and a third at the other, an operator's station adjacent to the two wheels, a U-shaped maintainer frame enclosing the third wheel and normally resting on the ground, pushing means pivoted to the maintainer and to the roller and means selectively operatable from the operator's station for shifting the single wheel for steering and for elevating or depressing the maintainer.
- 15 13. In a device of the class described, in combination with a wheel of a road roller, a maintainer blade extending parallel to the axis of the wheel supported on runners extending across the axis of the wheel, means between the roller and maintainer mechanism pressing it at four points onto the ground, means under the control of a single operator for changing the angular position of the wheel with reference to the maintainer and for varying the vertical position of the maintainer with reference to the wheel.
- 20 14. In a device of the class described, in combination with a wheel of a road roller, a maintainer blade extending parallel to the axis of the wheel, supported on runners extending across the axis of the wheel, means between the roller and maintainer mechanism pressing it at four points onto the ground, means under the control of a single operator for changing the angular position of the wheel with reference to the maintainer and for varying the vertical position of the maintainer with reference to the wheel.
- 25 15. In a device of the class described, in combination with a wheel of a road roller, a maintainer blade extending parallel to the axis of the wheel, supported on runners extending across the axis of the wheel, means between the roller and maintainer mechanism pressing it at four points onto the ground, means under the control of a single operator for changing the angular position of the wheel with reference to the maintainer and for varying the vertical position of the maintainer with reference to the wheel, and means for shifting the maintainer blade out of parallelism with the axis of the wheel.
- 30 16. In a device of the class described, in combination with a wheel of a road roller, a maintainer blade extending parallel to the axis of the wheel, supported on runners extending across the axis of the wheel, means between the roller and maintainer mechanism pressing it at four points onto the ground, means under the control of a single operator for changing the angular position of the wheel with reference to the maintainer and for varying the vertical position of the maintainer with reference to the wheel, and means for changing the vertical angular position of the maintainer blade.
- 35 17. In mechanism of the class described, a U-shaped frame resting on the ground having on its central portion a maintainer blade, its side arms acting as runners therefor; a pair of rods pivoted on opposite sides of said U-shaped frame near the juncture of the runners with the maintainer blade, spring mechanism tending to yieldingly maintain each of said arms at a given angular position with reference to its adjacent runner, and means engaging said rods between said spring mechanism and the maintainer blade for forcing the U-shaped frame into the ground for the purposes set forth. 70
- 40 18. In mechanism of the class described, a U-shaped frame resting on the ground having on its central portion a maintainer blade, its side arms acting as runners therefor; a pair of rods pivoted on opposite sides of said U-shaped frame near the juncture of the runners with the maintainer blade, spring mechanism tending to yieldingly maintain each of said arms at a given angular position with reference to its adjacent runner, and spring cushion means engaging said rods between said spring mechanism and the maintainer blade for forcing the U-shaped frame into the ground, for the purposes set forth. 80
- 45 19. In mechanism of the class described, a U-shaped frame resting on the ground having on its central portion a maintainer blade, its side arms acting as runners therefor; a pair of rods pivoted on opposite sides of said U-shaped frame, spring mechanism tending to yieldingly maintain each of said arms at a given angular position with reference to its adjacent runner, and means engaging said rods for forcing the U-shaped frame into the ground for the purposes set forth. 85
- 50 20. In mechanism of the class described, a U-shaped frame resting on the ground having on its central portion a maintainer blade, its side arms acting as runners therefor; a pair of rods pivoted on opposite sides of said U-shaped frame, spring mechanism tending to yieldingly maintain each of said arms at a given angular position with reference to its adjacent runner, and spring cushion means engaging said rods for forcing the U-shaped frame into the ground, for the purposes set forth. 90
- 55 21. In combination with a road roller, a maintainer blade in front of the roller, push rods connected to said maintainer blade, pivotally connected to the roller mechanism at 100
- 60 116
- 65 115
- 70 120
- 75 125
- 80 130

points only slightly above the maintainer blade, and a single means for selectively elevating the entire maintainer on said pivots for the purposes set forth.

5 22. In combination with a road roller, a maintainer blade in front of a roller and an adjustable extension on the end of said maintainer blade movable between two positions in one of which it is in alignment with the 10 blade and in the other of which it is clear of the end of said blade, and leaves the end free to do cutting work in a vertical line.

23. In combination with a road roller, a maintainer blade in front of a roller, an 15 adjustable extension on the end of said maintainer blade, and a pivotally mounted extension swingable between two positions in one of which it is in alignment with the blade and in the other of which it is clear of the 20 end of the blade, and leaves the end free to do cutting work in a vertical line.

24. In mechanism of the class described, a road roller carrying an operator's station, an operatively mounted maintainer, positively 25 pushed by the roller and means manipulatable by an operator at the station shifting the vertical position of the maintainer.

25. In mechanism of the class described, a U-shaped frame resting on the ground, 30 its central portion carrying a maintainer blade, while its side arms act as runners therefor, means for forcing said frame along the ground, means connected to said forcing means operating at two separated points 35 along each runner holding the runner on the ground.

26. In mechanism of the class described, a U-shaped frame resting on the ground, its central portion carrying a maintainer 40 blade, while its side arms act as runners therefor, means for forcing said frame along the ground, means connected to said forcing means operating at two separated points along each runner holding the runner 45 on the ground, and a spring in the said connections farthest from the blade.

27. In mechanism of the class described, a U-shaped frame resting on the ground, its central portion carrying a maintainer blade, 50 while its side arms act as runners therefor, means for forcing said frame along the ground, means connected to said forcing means operating at two separated points along each runner holding the runner on the 55 ground, and spring mechanism in said forcing means itself.

28. In mechanism of the class described, a U-shaped frame resting on the ground, its central portion carrying a maintainer blade, 60 while its side arms act as runners therefor, means for forcing said frame along the ground, means connected to said forcing means operating at two separated points along each runner holding the runner on the 65 ground, a spring in the said connections

farthest from the blade, and spring mechanism in said forcing means itself.

29. In mechanism of the class described, a U-shaped frame resting on the ground, 70 its central portion carrying a maintainer blade, while its side arms act as runners therefor, means for forcing said frame along the ground, means connected to said forcing means operating at two separated points along each runner holding the runner on 75 the ground, a moving road roller as the power behind said forcing means, and means operable by an operator carried by the roller for selectively lifting the frame clear of the road traveled and for adjusting 80 it to intermediate positions.

30. In mechanism of the class described, a U-shaped frame resting on the ground, 85 its central portion carrying a maintainer blade, while its side arms act as runners therefor, means for forcing said frame along the ground, means connected to said forcing means operating at two separated points along each runner holding the runner on 90 the ground, a spring in the said connections farthest from the blade, a moving road roller as the power behind said forcing means, and means operable by an operator carried by the roller for selectively lifting the frame clear of the road traveled 95 and for adjusting it to intermediate positions.

31. In mechanism of the class described, a U-shaped frame resting on the ground, 100 its central portion carrying a maintainer blade, while its side arms act as runners therefor, means for forcing said frame along the ground, means connected to said forcing means operating at two separated points along each runner holding the runner on 105 the ground, spring mechanism in said forcing means itself, a moving road roller as the power behind said forcing means, and means operable by an operator carried by the roller for selectively lifting the frame clear 110 of the road traveled and for adjusting it to intermediate positions.

32. In mechanism of the class described, a U-shaped frame resting on the ground, 115 its central portion carrying a maintainer blade, while its side arms act as runners therefor, means for forcing said frame along the ground, means connected to said forcing means operating at two separated points along each runner holding the runner on 120 the ground, a spring in the said connections farthest from the blade, spring mechanism in said forcing means itself, a moving road roller as the power behind said forcing means, and means operable by an operator carried by the roller for selectively lifting the frame clear of the road traveled and for adjusting it to intermediate positions.

33. In a machine of the class described, 125 in combination with a propelling mecha-

nism, a U-shaped road engaging frame having a road cutting blade as the center member of the frame, a pushing member intermediate connected between the ends of each side member of the frame extending in a diagonal direction to the propelling mechanism, and means more remote from the blade than the attachment points of said pushing means for pressing the side members of the frame onto the ground.

34. In a machine of the class described, in combination with a self-propelled road roller, a U-shaped road engaging frame having a road cutting blade as the center member of the frame, a pushing member intermediate connected between the ends of each side member of the frame extending in a diagonal direction to the road roller, and means more remote from the blade than the attachment points of said pushing means for pressing the side members of the frame onto the ground.

35. In mechanism of the class described, a maintainer blade, means for pushing it over the ground and spring mechanism behind the blade preventing its entering the ground too deeply.

36. In mechanism of the class described, a maintainer blade, means for pushing it over the ground and spring mechanism at some distance behind the blade engaging the pushing means preventing the blades entering the ground too deeply.

37. In a mechanism of the class described, in combination, a road roller, a maintainer mechanism, and manually controlled means operated from the roller for applying pressure, simultaneously, at four points on the maintainer mechanism.

38. In combination with an automotive vehicle, a maintainer blade, in front of said vehicle, delivering material to one side only of the machine, and an adjustable extension on each end of said blade.

39. In a machine of the class described,

a depth gauge mechanism, adapted for travel over the ground, a cutting blade carried by the depth gauge, and means selectively adjusting said blade vertically and diagonally relatively to said depth gauge mechanism.

40. In a machine of the class described, a depth gauge mechanism, adapted for travel over the ground, a cutting blade carried by the depth gauge, and means selectively adjusting said blade vertically and diagonally relatively to said depth gauge mechanism and for adjusting the angularity of the blade to vertical plane.

41. In a machine of the class described, a depth gauge mechanism, adapted for travel over the ground, a cutting blade carried by the depth gauge, and means selectively adjusting said blade vertically and diagonally relatively to said depth gauge mechanism and for adjusting the angularity of the blade to vertical plane and for selectively extending the length of the blade.

42. In a road roller, a cutting blade carried by the roller over the ground and means selectively adjusting the blade both vertically and diagonally.

43. In a road roller, a cutting blade carried by the roller over the ground, means selectively adjusting the blade both vertically and diagonally, and for adjusting the angularity of the blade to a vertical plane.

44. In a road roller, a cutting blade carried by the roller over the ground, means selectively adjusting the blade both vertically and diagonally, for adjusting the angularity of the blade to a vertical plane, and for selectively extending the length of the blade.

In witness whereof, we have hereunto subscribed our names.

WILLIAM T. BEATTY.
FRANK S. DAVIS.
FRED D. WILSON.
